(57) **CLAIM**

The ornamental design for a razor handle, as shown and described.

DESCRIPTION

FIG. 1 is a front, top, perspective view of a razor handle; FIG. 2 is a right-side perspective view thereof; FIG. 3 is a left-side perspective view thereof; FIG. 4 is a front view thereof; FIG. 5 is a rear view thereof; FIG. 6 is a top view thereof; and, FIG. 7 is a bottom view thereof. In the drawings, the broken lines illustrate portions of the razor handle and form no part of the claimed design.
